United States Patent Office

Des. 207,259
Patented Mar. 28, 1967

207,259

VEHICLE CHAIR

Chester J. Barecki, Grand Rapids, Mich., assignor to American Seating Company, Grand Rapids, Mich., a corporation of New Jersey

Filed Jan. 14, 1966, Ser. No. 605

Term of patent 14 years

(Cl. D15—8)

FIG. 1

FIGURE 1 is a perspective view of the chair showing the front portion thereof, and showing my new design; and

The end of the chair not shown is of conventional configuration.

I claim:

The ornamental design for a vehicle chair, as shown and described.
